UNITED STATES PATENT OFFICE.

MARSDON D. RANSOM, OF GEORGETOWN, SOUTH CAROLINA.

LOCK BOTTLE-FASTENER.

No. 896,938.

Specification of Letters Patent. Patented Aug. 25, 1908.

Application filed March 1, 1907. Serial No. 360,009.

To all whom it may concern:

Be it known that I, MARSDON D. RANSOM, a citizen of the United States, residing at Georgetown, in the county of Georgetown 5 and State of South Carolina, have invented a new and useful Improvement in Lock Bottle-Fasteners, of which the following is a specification.

This invention relates to stopper fasteners 10 and more particularly to lock stopper fasteners, the object being to provide a fastener which can be easily and quickly attached to the neck of the ordinary bottle, so that it is impossible to remove the stopper without a 15 key.

With this and other objects in view, the invention consists in the novel features of construction, combination and arrangement of parts hereinafter fully described and 20 pointed out in the claims.

In the drawing forming a part of this specification: Figure 1 is a perspective view of a portion of a bottle neck showing my stopper fastener arranged thereon. Fig. 2 is a front 25 view of my improved stopper fastener detached. Fig. 3 is a rear view of the fastener detached.

In the drawing A and B indicate a pair of 30 duplicate semi-circular bands provided with angle apertured ends A', A²', B', B²'. The angled ends A', B' are spaced apart by a bolt C which securely fastens the bands around the neck of the bottle. Pivotaly mounted on the bolt C between the ends A' B' is a 35 sleeve D² of a depending tongue D' projecting out from one side of a disk D which is adapted to fit over the stopper of the bottle, and is provided with an oppositely disposed depending tongue D³ having a slot D⁴ formed 40 therein, adjacent its free end which is adapt-

ed to fit over the angled ends A² B² and secure the two together around the neck of the bottle. An ordinary padlock E is then inserted through the apertures in the end of the bands and the stopper will be securely locked in the 45 bottle. It is of course understood that the ends can be connected together by a seal lock or any other suitable lock as desired.

From the foregoing description it will be readily seen that I have provided a very novel 50 fastener for securing the stopper with locking means in the bottle so that the stopper can not be removed without a key.

Having thus fully described my invention, what I claim as new and desire to secure by 55 Letters Patent is:—

1. In a device of the kind described, the combination with a bottle and its stopper, of a pair of semi-circular bands having angled ends arranged around the neck of said bottle, 60 and a disk pivotally mounted between one pair of angled ends of said bands, provided with a tongue adapted to fit over the other pair of angled ends.

2. In a device of the kind described, the 65 combination with a bottle and its stopper, of a duplicate pair of semi-circular bands adapted to fit around the neck of said bottle and provided with angled apertured ends, a bolt connecting one pair of apertured ends, a 70 tongue carried by a disk pivotally mounted on said bolt, a depending slotted tongue formed on said disk adapted to fit over the other pair of angled ends, and a padlock adapted to connect said ends and prevent 75 said tongue from coming off said ends.

MARSDON D. RANSOM.
